CALF FEEDER

Mathew H. Stapleton, National Ave., Jefferson, Iowa

Filed July 9, 1963, Ser. No. 75,720

Term of patent 14 years

(Cl. D12—2)

Fig. 1

Fig. 2

Fig. 3

FIG. 1 is a top plan view of a calf feeder showing my new design;

FIG. 2 is a perspective view thereof on a reduced scale; and

FIG. 3 is an elevational view of the calf feeder.

The undisclosed side of the calf feeder is substantially the same in appearance as the side shown in FIG. 3.

I claim:

The ornamental design for a calf feeder, substantially as shown and described.
